UNITED STATES PATENT OFFICE.

WALTER S. ADAMS, OF PHILADELPHIA, PENNSYLVANIA, ASSIGNOR TO
JOHN A. BRILL, OF SAME PLACE.

CAR-TRUCK.

SPECIFICATION forming part of Letters Patent No. 566,118, dated August 18, 1896.

Application filed March 20, 1894. Serial No. 504,402. (No model.)

To all whom it may concern:

Be it known that I, WALTER S. ADAMS, a citizen of the United States, residing at Philadelphia, in the county of Philadelphia and State of Pennsylvania, have made certain new and useful Improvements in Car-Trucks, of which the following is a specification.

My invention relates more particularly to pivotal car-trucks of the four-wheel class wherein an equalizing-bar is utilized for the purpose of distributing the weight of the superposed car evenly upon all of the wheels of the truck and to support the truck-bolster, my invention, however, being capable of use in other structures.

The particular object of my present invention is to improve the bolster construction.

My invention therefore consists substantially in the bolster construction hereinafter described, and more fully pointed out in the claims.

In the drawings forming part of this specification, Figure 1 is a plan view of a truck complete embodying my improvements; Fig. 2, a side elevation; Fig. 3, a sectional elevation taken approximately on the line xx , Fig. 1; Fig. 4, a rear elevation, partly in section, approximately on the line yy , Fig. 2; and Fig. 5, a fragmentary perspective view of one end of the transom.

Similar numerals of reference refer to like parts throughout the several views.

Before proceeding with the description of the details of construction illustrated herein I will give a short description of the general plan of structure adopted in this class of trucks, so that my invention can be better understood.

In four or six wheel trucks of the pivotal class the frame is usually composed of wheel-pieces and cross-bars, the wheel-pieces carrying pedestals or horn-plates which secure the axle-boxes and axles in position and preserve their parallelism. Between the wheels longitudinally and finding a support upon the top of the axle-boxes on each side of the truck are what are known as "equalizing-bars," upon which equalizing-bars rest the equalizing-springs, and upon these springs rests the car-frame, the equalizing-bar being used to distribute the weight of the car evenly on all the

wheels. Almost invariably this equalizing-bar has a central depression lying between its points of support on the axle-boxes. Thus it will be seen that the words "truck-frame" 55 are to be distinguished from other parts in the truck structure by the function which it performs, to wit: a structure composed of wooden beams or iron bars, to which the journal-boxes or pedestals, springs, and other 60 loose parts are attached, and which forms the skeleton of the truck, and by means of which the parallelism of the axles is preserved. An equalizing-bar may be thus defined: a wrought-iron bar which bears on the top of 65 the journal-boxes and which extends longitudinally from one to the other, the sole function of which is to transfer part of the weight of the car on one wheel to the other, and thus equalize it on both.

In the forms of pivotal trucks now in use the truck-frame rests upon the equalizing-springs which find a support upon the equalizing-bar and it upon the axle-boxes. In my construction I have reversed this order of arrangement and provided a truck-frame which rests upon the axle-boxes, in which are formed pedestals for preserving the parallelism of the axles, and upon the frame I have located the equalizing-springs, and upon these springs 80 the equalizing-bars, to which are secured the parts necessary to support a truck-bolster.

In the old style of truck the truck-frame is movable up and down in relation to the axles in accordance with the compression of 85 the equalizing or other truck springs, and the equalizing-bar remains stationary on its support upon the axle-boxes.

In my structure the truck-frame does not move, nor is its position of rest upon the axle-boxes affected by the movement of the equalizing or other truck springs, and the equalizing-bar is made to take the place of the truck-frame in moving up and down with such springs.

By so constructing the truck-frame that it will lie below the equalizing-bar and the equalizing-bar occupy a position a very little higher than in the old form of structure I am able to give the superposed car its proper 100 bearings on the truck at a point very much below the top of the wheel, and in fact nearer

the axle than to the top of the wheel. Of course this is a matter of adjustment, the main point being that the car finds a bearing upon the truck at a point considerably below 5 the tops of the wheels, whereas in the old form the top of the truck is not only substantially as high as the wheel, and in many cases above it, but the truck-bearings are considerably above the tops of the wheels.

10 Among the resulting benefits of my construction, as compared with that of the old trucks, is that I can place a car-body much nearer the axles in a vertical plane, which results in getting the center of gravity much 15 closer to the track or final support of the car, and incidentally reduces the number of steps necessary for forming an exit or entrance to the car, and, further, enables a very low station-platform to be used, wherefrom the passenger may enter or alight from the car without the use of any steps whatever.

I will now describe the general structure of my truck, calling attention to the fact that the various novel features of construction 25 can be used in other relations without departing from the spirit of my invention.

The numeral 1 indicates the truck-wheels of an ordinary four-wheel truck, 2 the axles therefor, and 3 the axle-boxes, of usual or 30 any desired construction.

The truck-frame in this case is of the type known as an "axle-box" frame, the leading feature or characteristic of which is that it is supported upon the axle-boxes, acts as a 35 truck-frame in preserving the parallelism of the axles, has pedestals for confining and guiding the axle-boxes, and remains substantially unaffected by the movement of the car upon the truck-springs, wholly unaffected 40 when supported on the axle-boxes metal to metal, and substantially unaffected when supported on the axle-boxes by means of a rubber or other cushion designed solely for the purpose of deadening the shock on the 45 axle-boxes, the compression of said cushion being very slight, and which is wholly inadequate in this relation to resiliently support the car-body, and is not to be confounded with what are termed the "car-springs" which 50 are used solely to resiliently support the car-body. My invention is not limited, however, to the use of an axle-box frame, as the usual bolster-springs may be dispensed with and the car-springs located either between the 55 truck-frame and the equalizing-bar or between the axle-box pedestals and the axle-boxes or in both positions.

The numeral 4 designates inverted-U-shaped yokes acting as pedestals for the axle-boxes 60 3, from the lower arms of which extend the extensions 5, and which are united by the end cross-bar 6, the inner upright 7 of the yokes extending below the plane of the extensions 5, and which are united by a side 65 bar 8, lying below the lowest part of yoke members. All of these parts may be made separate and bolted together, if desired; but

I prefer that these parts be made into a single piece of metal homogeneous throughout, so as to do away with the necessity of bolts for 70 uniting the parts, which weaken the structure, and which may be assembled by the process of welding, drop-forging, or any of the well-known ways.

Between the under side of the yokes and 75 the tops of the axle-boxes are located the rubber or other spring cushions 9, before referred to. This frame entirely encircles or incloses the wheels and is at all of its parts much lower than the top of the wheels, and 80 all of those parts, excepting a portion of the yokes, are on the same plane with or below the axles, the side bars being much below the axles.

Upon the side bars 8 rest the equalizing-spring seats 10, which receive the equalizing-springs 11, of coil form and disposed vertically, which support in their turn the equalizing-spring caps 12, the caps in turn supporting the equalizing-bar 13, the web of which 90 is disposed vertically, and which is provided at its ends with a bifurcated enlargement 14, which embraces and is adapted to play up and down (or laterally, if desired) upon the inner uprights 7 of the axle-box yokes 4, 95 which guides the equalizing-bar and limits or restrains its transverse movement, the axle-boxes being provided with flanges 15, in which the yokes 4 are set so as to preserve them in their proper relations to each other and back 100 up the uprights 7 in their limiting or restraining the tendency to a transverse movement of the equalizing-bar. As both sides of the axle-box or truck-frame (my invention, when broadly considered, enabling me to use these 105 terms synonymously) are constructed alike, the description of the construction of one side will answer for both, and that of the equalizing springs and bar, &c., on one side being the same as on the other will answer for both. 110

The truck-bolster is resiliently supported upon the equalizing-bar, and the equalizing-bar in turn upon the truck-frame.

Although I do not limit myself to any special form of bolster structure, nor to resiliently supporting it upon the equalizing-bar, I, however, prefer the structure now to be described.

From the equalizing-bars transversely of the truck extend the transoms 16, in this case formed of a channel-iron having a vertical web 17, lateral webs 18, the vertical web 17 being cut away to receive the equalizing-bar, as shown in Fig. 5, the ends of the lateral webs 18 resting upon the equalizing-bar 13, the vertical web 17 being disposed inwardly, as shown in Figs. 1 and 4 most clearly. Upon the top of the transoms 16, at suitable intervals apart, are secured the swing-hanger pivot-bearings 19, of usual or desired construction, between which extend the upper swing-hanger pivots 20, from which pivots depend the swing-hangers 21, which engage, at their lower extremities, with the lower swing-

hanger pivots 22, the ends of which find bearings in the spring-plank bearings 23, which are rigidly secured to the spring-plank 24, upon which the elliptical or other form of 5 bolster-spring 25 is secured, upon which spring rests the truck-bolster 26, the sides of which lie adjacent to the vertical web 17 of the transoms 16. On the top of the bolster the truck-center bearing 27 is secured, of any desired 10 construction and height, preferably low to permit of the car-body being placed low, and upon the bolster, at any desired points removed from the center bearing, may be located the usual side bearings. This form of 15 bolster suspension enables the car to swing transversely independent of the truck, but if this feature is not desired the bolster can be rigidly secured to the equalizing-bars and the car-springs arranged as before set forth.

20 By reason of the truck-frame being disposed or located below the equalizing-bar between the axle-boxes, and the bolster connections being made directly to the equalizing-bar, I am enabled to obtain a truck structure having, among other benefits, either enumerated 25 or non-enumerated, that of getting a very low-placed car-body.

It is apparent that many changes and modi-

fications can be made in the present structure without departing from the spirit of my invention. 30

Having described my invention, I claim—

1. In a car-truck, the combination, with the truck-frame, of the transoms formed of channel-iron, with bifurcated or notched ends embracing a member of said frame, having vertical webs opposed to each other, and a bolster supported between and from the transoms adapted to bear against said vertical webs, substantially as described. 35

2. In a car-truck, the combination, with the bars 13, of the transoms 16 having a vertical web 17 and horizontal webs 18, the web 17 being cut away to form extensions of the webs 18, which webs embrace the bars 13, pivot-blocks 19 on the webs 18, pivots extending between the blocks, links, and a bolster supported by the pivots, substantially as described. 40

Signed at Philadelphia, in the county of 50 Philadelphia and State of Pennsylvania, this 28th day of February, 1894.

WALTER S. ADAMS.
